M. J. TRUMBLE

COMBINED DISTILLING AND CRACKING PROCESS AND APPARATUS THEREFOR

Filed Sept. 8, 1924

INVENTOR:
MILON. J. TRUMBLE.

BY,
Fred W. Bain
ATTORNEY.

UNITED STATES PATENT OFFICE.

MILON J. TRUMBLE, OF LOS ANGELES, CALIFORNIA.

COMBINED DISTILLING AND CRACKING PROCESS AND APPARATUS THEREFOR.

Application filed September 8, 1924. Serial No. 736,434.

My invention relates to the art of producing volatile hydrocarbons from raw materials such as shale, coal, lignite and the like.

It is an object of my invention to provide a process and apparatus by which the hydrocarbon content of such solid materials may be removed and converted into low boiling point hydrocarbons.

It is a well known fact that solid raw materials of the general character described above are capable of yielding hydrocarbon oils which, however, do not at the present time have any considerable importance in the United States, due to the character of the oil ordinarily produced and the excessive cost of production when produced by the present well known means.

It is an object of my invention to provide a process and apparatus by which low boiling point hydrocarbons having a high commercial value can be economically produced.

Further objects and advantages of the invention will be made evident hereinafter.

Referring to the drawing which is entirely diagrammatic,

I employ a retort 1, a prime mover 2, a primary condenser 3, a cracking still 4, a secondary condenser 5, and a transfer pump 6.

The retort 1 may be of any convenient form suited to operate under pressure and adapted to be readily charged with the raw material to be treated. It is provided with a pipe 11 for the admission of steam which is used as a heating medium and vapor is taken off through a pipe 12. This vapor may be at a pressure of 150 pounds or more, and substantially saturated under the existing conditions of temperature (below 800° F.) and pressure. This vapor is delivered to the prime mover 2, which consists of a steam turbine reciprocating engine or the like directly connected to an electric generator 21. In the prime mover 2 the expansive force of the vapor is used to produce electric power, which is delivered by the generator 21. The vapors from the exhaust side of the prime mover 2 are delivered through a pipe 23 into the primary condenser 3. This condenser is preferably water-cooled, water being delivered thereto through a pipe 31 and removed through a pipe 32. Certain uncondensed portions of the vapor may be delivered through a pipe

33 to the secondary condenser 5, where they are condensed and delivered through a pipe 51 to suitable storage, not shown. The condenser may be cooled by cooling water delivered through a pipe 52 and withdrawn through a pipe 53. The heavier condensates produced in the primary condenser 3 are delivered through a pipe 61 to the transfer pump 6 and are forced by this pump through a pipe 62 into the still 4. This still may be any convenient form of cracking still, with suitable heating means, not shown, such as direct fire, steam or the like. The heating means should be capable of sufficiently raising the temperature of the oil in the still 4 to produce a cracking reaction. The vapors delivered through the pipe 43 from the still 4 may be at a temperature of about 800 degrees Fahrenheit. These vapors are delivered into the pipe 12 and by this pipe are delivered to the prime mover 2.

The method of operation is as follows:

The retort 1 being charged with any of the above specified raw materials, steam is applied thereto through the pipe 11 and the hydrocarbons carried in the raw material are distilled and carried over with the steam through the pipe 12 to the prime mover 2, where they are utilized. The exhaust gases from the prime mover pass to the primary condenser 3, where the heavier portion is condensed and delivered under pressure by the pump 6 into the cracking still 4. The lighter portion of these vapors passes through the primary condenser 3 without material condensation, and are condensed in the secondary condenser 5, being delivered as a final product through the pipe 51. At the present time it is most economical to run the apparatus so that gasoline and certain valuable by-products are delivered through the pipe 51. The heavy condensates delivered through the pipe 62 are subjected to sufficient heat and pressure in the still 4 to cause a cracking reaction to take place, and the vapors passing over through the pipe 43 consist largely of gasoline.

The conception of mixing the low temperature vapors from the retort 1 with the high temperature vapors from the cracking still 4 is original with me, and produces certain new and useful results. The vapors from the retort 1 are substantially the usual heavy oil vapors produced by the distilla-

2
tion of solid raw materials, such as shale, coal, or the like. The vapors are substantially saturated vapors containing high boiling point tars and oils which will readily condense if the vapors are even slightly cooled.

10 If an attempt were made to operate the prime mover 2 on such vapors, there would be an immediate deposition of these tars on the various surfaces of the prime mover, with consequent clogging of the mechanism, rapid wear of the parts, and ultimate stoppage.

15 The vapors from the still 4 are, however, almost wholly low boiling point vapors which, when condensed, form gasoline or other solvent oils. By combining the vapors from the retort 1 and the still 4 in the pipe 12, I form a combined vapor at a higher 20 temperature than the retort vapors, thus preventing subsequent condensation of the tars therefrom in the prime mover 2 and thus making possible the continuous operation of the prime mover 2.

25 I claim as my invention:

1. An apparatus for refining hydrocarbons comprising: a retort adapted to receive raw material yielding vapors too cool and heavy for use alone in a prime mover; means for heating said retort to a sufficient temperature to cause a distillation of said heavy vapors from said raw material; a cracking still; means for heating the cracking still to a considerably higher temperature than 30 the average distillation temperature in said retort; a prime mover; means for passing the combined vapors from said retort and said cracking still through said prime mover; and means for supplying oil to said cracking still.

40 2. An apparatus for refining hydrocarbons comprising: a retort adapted to receive raw material yielding vapors too cool and heavy for use alone in a prime mover; means for heating said retort to a sufficient temperature to cause a distillation of said heavy vapors from said raw material; a cracking still; means for heating the cracking still to a considerably higher temperature than 45 the average distillation temperature in said retort; a prime mover; means for passing the combined vapors from said retort and said cracking still through said prime mover; means for condensing a portion of 50 the exhaust vapors from said prime mover; and means for passing the condensate so produced into said still.

55 3. An apparatus for refining hydrocarbons comprising: a retort adapted to receive raw material yielding vapors too cool and heavy for use alone in a prime mover; means for heating said retort to a sufficient temperature to cause a distillation of said heavy vapors from said raw material; a cracking still; means for heating the crack-

ing still to a considerably higher temperature than the average distillation temperature in said retort; a prime mover; means for passing the combined vapors from said retort and said cracking still through said prime mover; means for condensing a portion of the exhaust vapors from said prime mover; a pump; means for delivering the condensed portion of said exhaust vapors to the suction side of said pump; and means for delivering said portion under pressure from said pump into said still.

4. An apparatus for refining hydrocarbons comprising: a retort adapted to receive raw material yielding vapors too cool and heavy for use alone in a prime mover; means for passing steam into said retort to cause a distillation of said heavy vapors from said raw material; a cracking still; means for heating the cracking still to a considerably higher temperature than the average distillation temperature in said retort; a prime mover; means for passing the combined vapors from said retort and said cracking still through said prime mover; and means for supplying oil to said cracking still.

5. An apparatus for refining hydrocarbons comprising: a retort adapted to receive raw material yielding vapors too cool and heavy for use alone in a prime mover; means for passing steam into said retort to cause a distillation of said heavy vapors from said raw material; a cracking still; means for heating the cracking still to a considerably higher temperature than the average distillation temperature in said retort; a prime mover; means for passing the combined vapors from said retort and said cracking still through said prime mover; means for condensing a portion of the exhaust vapors from said prime mover; and means for passing the condensate so produced into said still.

6. An apparatus for refining hydrocarbons comprising: a retort adapted to receive raw material yielding vapors too cool and heavy for use alone in a prime mover; means for passing steam into said retort to cause a distillation of said heavy vapors from said raw material; a cracking still; means for heating the cracking still to a considerably higher temperature than the average distillation temperature in said retort; a prime mover; means for passing the combined vapors from said retort and said cracking still through said prime mover; means for condensing a portion of the exhaust vapors from said prime mover; a pump; means for delivering the condensed portion of said exhaust vapors to the suction side of said pump; and means for delivering said portion under pressure from said pump into said still.

7. A method of obtaining power, inci-

dentially to the recovery of values from carbonaceous materials initially yielding vapors too cool and heavy for successful use alone in the operation of a prime mover,
5 which comprises: combining such vapors not only with steam but with hotter vapors from a cracking still and thereafter passing the

combined vapors through a prime mover and thence through a condenser.

In testimony whereof, I have hereunto set 10
my hand at Los Angeles, California, this
2nd day of Sept., 1924.

MILON J. TRUMBLE.
